UNITED STATES PATENT OFFICE.

NEUTON D. RICHARDS, OF LOS ANGELES, CALIFORNIA.

DESIGN FOR A BUCKLE.

Application filed April 8, 1925. Serial No. 13,066. Term of patent 3½ years.

To all whom it may concern:

Be it known that I, NEUTON D. RICHARDS, a citizen of the United States, residing at Los Angeles, in the county of Los Angeles and State of California, have invented a new, original, and ornamental Design for a Buckle, of which the following is a specification, reference being had to the accompanying drawing, forming a part thereof.

Figure 1 is a front view of a buckle showing my new design.

Fig. 2 is a bottom edge view of the buckle shown in Fig. 1.

I claim:

The ornamental design for a buckle, as shown.

Signed at Los Angeles, in the county of Los Angeles, and State of California, this 2nd day of April, 1925.

NEUTON D. RICHARDS.

Witness:

ARTHUR F. LARRABEE.
